(57) **CLAIM**

The ornamental design for a golf glove, as shown and described.

DESCRIPTION

FIG. 1 is a top perspective view of the golf glove of this invention;

FIG. 2 is an elevation view of a closed finger-tip end portion of the golf glove of this invention;

FIG. 3 is a medial side elevation view of the golf glove of this invention;

FIG. 4 is a plan view of a back portion of the golf glove of this invention;

FIG. 5 is an elevation view of an open wrist end portion of the golf glove of this invention;

FIG. 6 is a plan view of a front portion of the golf glove of this invention; and,

FIG. 7 is a lateral side elevation view of the golf glove of this invention.

The thicker, shorter-incremented broken lines shown on the shaded surface of the glove depict stitching and form a part of the claimed design. The thinner, longer-incremented broken lines that depict a logo within a hollow circle on the fastening tab represent unclaimed features of the article in which the claimed design is embodied. The broken line illustrated within the interior portion of the glove represents the bounds of the claim and does not form part of the claimed design.
